UNITED STATES PATENT OFFICE.

GEORGE W. PRICE, OF BALTIMORE, MARYLAND, ASSIGNOR TO WILLIAM J. HOOPER, OF SAME PLACE.

MACHINE FOR MAKING TWINE, &c.

SPECIFICATION forming part of Letters Patent No. 364,371, dated June 7, 1887.

Application filed May 17, 1886. Serial No. 202,382. (No model.)

To all whom it may concern:

Be it known that I, GEORGE W. PRICE, of the city of Baltimore and State of Maryland, have invented a new and Improved Machine 5 for Making Twine, &c., of which the following is a full description.

In the drawings, Figure 1 is a perspective view of the upper part of my machine, showing parts of the supports or framing in section; Fig. 2, a sectional view of the parts shown in Fig. 1, the supports and reel being omitted and one of the flier-arms broken away. Fig. 3 is an illustration, partly in elevation and partly in section, of the lower part 15 of my apparatus, showing one of the strand-spindles with its appurtenances; Fig. 4, an upright view of the entire device; Fig. 5, a plan view taken on line $\alpha\alpha$ of Fig. 4.

Upon a base, A, viewing Figs. 3 and 4, I 20 have erected the yoked standards B, to the top of each of which is secured the pinion b . The upright shaft or spindle b' passes through the yoked standard and rests in a socket, b^2 . It is provided with a pulley, b^3 , through which 25 a revolving motion is imparted to the shaft or spindle b' . To the upper end of this spindle is screwed or otherwise secured the hollow sleeve b^4 , and this sleeve is provided with the arms b^5 . Into this sleeve is placed the hollow 30 spindle b^6 , which carries on its upper end the pinion b^7 and the plate b^8 , and this plate is provided with the pins b^9 . The upright spindle C, provided with the base-plate c' , constituting the bobbin support, rests upon the plate 35 b^8 , and is provided with sockets to fit over the pins b^9 . One of the arms b^5 is perforated to admit the shaft b^{10} , which passes loosely 40 through the arm, and is provided with a shoulder to form a bearing upon the arm. At 45 its upper end the said shaft b^{10} is provided with the pinion b^{11} and at its lower end with the pinion b^{12} , meshing, respectively, with the pinions b^7 and b . Upon the spindle C is placed 50 loosely the spool c^2 . From the ends of the arms b^5 project upwardly the rods or wires b^{13} , which are joined at their upper ends so as to revolve loosely about the hollow socket-piece c^3 , which is fixed to the cross-beam A'. One 55 of the rods b^{13} is provided with an eye, b^{14} , to admit the passage of the strand or yarn. 60 This strand (marked d) is wound around the

spool, and passes thence first through the eye c^4 , which is attached to the plate b^8 , then between the plates c' and b^8 , through a groove in the plate c' , down through the hollow spindle 55 b^6 and pinion b^7 , out through an aperture in the sleeve b^4 , then up through the eye b^{14} , and out through the hollow piece c^3 .

The foregoing is a description of the lower part of the twine-machine—that part which 60 prepares the strand for the other part of the machine.

Its mode of operation is as follows: The upright shaft b' revolves, turning with it the sleeve b^4 and the arms b^5 . The friction upon the 65 spool c^2 would cause it to revolve were it not for the arrangement of the shaft b^{10} with its pinions b^{11} b^{12} meshing with the pinions b^7 and b . As the arms b^5 revolve, carrying with them the spindle b^{10} and turning the pinion b^{12} 70 around the stationary pinion b , a revolving motion is imparted to the spindle b^{10} in the same direction as the motion of the arms b^5 . As the pinion b is stationary and the shaft b^{10} with its pinions revolves around it, the pinion b^7 is 75 thus prevented from turning and the spool remains motionless, turning only as the strand is drawn off to supply the necessary feed. These strands are caused to be fed from the spools by the draft on the strands produced 80 by the upper devices of the machine. Any number of spools may be used. Figs. 4 and 5 show three. When the strands d pass through and out of the socket-pieces c^3 , they are brought together and passed into the upper part of the machine, where they are properly laid into twine or cord.

It will be seen that as the spool c^2 is stationary and the arms b^5 revolve, carrying and turning with them the strand or yarn d , a 90 twist is given to the strand with each revolution of the arms b^5 at the lower part of the strand between the eye b^{14} and the eye c^4 . It will also be seen that as the strand d above the eye b^{14} is held by the upper part of the 95 machine another twist is given to the yarn above the eye b^{14} , and thus with each revolution of the arms b^5 a double twist is given to the strand.

I will now describe that part of the machine 100 which lays the strands into cord.

The cross-bar of the frame work A' serves

as a support and journal for the upright hollow shaft E, viewing Figs. 1, 2, and 4. Attached to this shaft, at its upper end, is the pulley e, and at its upper end the bracket E'. 5 This bracket is constructed with the opening e² and the arms e³ e⁴. Secured to the upper part of this bracket is the upright shaft e⁵, which has secured to its upper end, so as to revolve with it, the pinion e⁶. A frame, e⁷, is slipped over the upright shaft, the upper part of which contains a socket, into which the end of the shaft e⁵ enters, as shown at e⁸, Fig. 2. A sleeve, e⁹, passes through an opening in the frame e⁷ and surrounds loosely the shaft e⁵. 15 To the upper end of this sleeve is attached the pinion e¹⁰ and below the frame the pulleys H H. Another sleeve e¹¹, is slipped over the shaft e⁵ and fills the space between the two pinions e⁶ and e¹⁰. The frame e⁷ is also provided 20 with the cross-bar e¹², which provides a journal for the spindle e¹³, which carries on its ends the pinions e¹⁴ and e¹⁵, meshing, respectively, into the pinions e⁶ and e¹⁰. Into the top of the frame e⁷ is screwed or otherwise secured 25 the upright shaft e¹⁶, (see Fig. 2,) and over this shaft is slipped loosely the reel I. The top of the shaft e¹⁶ is squared at e¹⁷, over which the sleeve e¹⁸ is slipped, which is provided with a socket conforming in shape to the squared 30 part of the shaft e¹⁷, and this sleeve has its bearing in the cross-beam A³, and may be provided with projections e¹⁹, or any other means for securing it to the cross-beam A³. The arms e³ and e⁴ are provided with the projections or lugs h, which may be of any number 35 to correspond with the number of pulleys H. In the drawings three of these pulleys are shown; but one is sufficient, and the others are placed there to give the operator control 40 of the speed. The pinions e⁶ and e¹⁰ have a different number of teeth—that is to say, pinion e⁶ has fewer teeth than pinion e¹⁰. Consequently the pinions e¹⁴ e¹⁵ have also a different number of teeth, arranged with their positions 45 reversed. The object of this arrangement is to cause the pulleys H to travel more slowly than the flier-arm e⁴, in order that a draft may be created to pull off the twine as it is fed. As the twine is wound around the pulley H, 50 which revolves with its sleeve e⁹ upon the shaft e⁵, it will be seen that the pulley, if allowed to travel in the same direction with the flier and a little slower, will create a drag upon the twine and feed it to the flier-arm. The 55 reel i, which is revolved by the drag of the twine from the flier-arm e⁴, is restrained in its movement by the friction of its seat upon the tops of frame e⁷, and this friction is sufficient to retard the reel, so that the twine may be 60 wound upon it.

The strands d d d, proceeding from the lower part of the machine, are brought up and united as they enter the upper part of the machine, and passed through the hollow shaft E, then 65 up and around the arm e³, over one of the lugs h, one or more times around the pulley H, then under one of the lugs h on the arm or

flier e⁴, then up back of the arm and through the eye e²⁰, and fastened to one of the arms of the reel I.

If the cord be coiled around the pulleys H in the direction opposite to that of the rotation of the flier, as indicated in the drawings, it is evident that, in order to produce the required pull on the cord, the pulley H must 75 rotate more slowly than the flier, and to this end the several gears are arranged as shown. By these means the completed cord is fed slowly out toward the arm e⁴ of the flier. The cord passes from the arm e⁴ through the eye e²⁰ to the reel I, and is attached thereto. Now, if the reel I were stationary the cord would be wound thereon so rapidly by the rotation of the flier as to break the cord at once, or to draw it through so rapidly as to 85 prevent the proper twist. On the other hand, if the reel were allowed to rotate freely, the resistance of the cord upon the flier-arm and through the eye and its weight would draw the reel around and no winding would take 90 place. Therefore, the reel must be mounted so as to rotate upon the shaft e¹⁶, but with sufficient friction to overcome the weight and resistance of the cord upon the flier-arm.

The upper devices of the machine are set in 95 motion by applying a belt to the pulley e, so as to turn in a direction which will partially untwist the strands of thread coming from the spools and lay or twist together the strands. This is done to produce a proper lay of the 100 threads in forming the completed cord. As the machine works it will be readily seen that the strands will be twisted into a cord, and as the reel does not revolve as rapidly as the flier the finished cord will be wound upon the reel. 105

What I claim is—

1. The combination of the stationary spool-support C c', the plate b⁸, supporting the plate c' and having a groove for the passage of the strand, the spindle b', and rods b¹³, one of which 110 has the eye b¹⁴, the socket-piece c³, the sleeve b⁴, located below the spool-spindle and provided with the arms b⁵, and means, substantially as described, for supporting and restraining from rotation the plate b⁸, substantially as described. 115

2. The combination of the standard B and spindle b', stationary pinion b, rods b¹³, one of which has the eye b¹⁴, the socket-piece c³, the sleeve b⁴, provided with the arms b⁵, the spindle b¹⁰, with its pinions, the hollow spindle b⁶, 120 inserted in sleeve b⁴ and carrying the pinion b⁷ and plate b⁸, the spool-spindle C, and plate c', resting on the plate b⁸, substantially as described.

3. The combination of the yoked standard 125 having the pinion b, secured to the top, the upright spindle b', passing through the yoked standard and resting in the socket or bearing b², the hollow sleeve b⁴, secured to the upper end of the spindle b', having an aperture at its 130 side and provided with the arms b⁵, the rods b¹³, one of which has the eye b¹⁴, the socket-piece c³, the hollow spindle b⁶, located within the sleeve b⁴, and having on its upper end the

pinion b^7 , the plate b^8 , provided with the pins b^9 , upright spool-spindle C, provided with the base-plate c' , resting upon the plate b^8 , the shaft b^{10} , having its bearing in the arm b^5 , and provided with the pinions b^{11} and b^{12} , substantially as described and shown.

4. The bracket E and upright revolving spindle e^5 , in combination with the hollow shaft e^8 , the pinion e^6 , and the pinion e^{10} , having a differ-

ent number of teeth, the spindle e^{13} , carrying to the pinions e^{14} and e^{15} , having also a different number of teeth arranged in reverse order, the bracket e^7 , and the pulley H.
